UNITED STATES PATENT OFFICE

2,441,394

VIBRATION AND MASSAGE APPARATUS

Perl L. Bucy, Oklahoma City, Okla.

Application February 7, 1945, Serial No. 576,598

8 Claims. (Cl. 128—63)

1

This invention relates to therapeutic apparatus and pertains more particularly to improvements in machines for imparting vibration to, and effecting the stimulation of, the human body.

It is well-known to the medical profession and others that regular and systematic movements of the muscular and other tissues of the body are essential to the maintenance of proper health, because of the fact that by this means there is maintained through the tissues a proper circulation of blood for the supply of nourishment to the cells of which the tissues are made up and also by such means, the waste products of the tissues, such as broken down cells and the like, are removed from the system. In those persons who are physically fit regular exercise is essential to accomplish these results and where a person becomes nervously exhausted so that the taking of continued exercise is not feasible, a wasting and weakening of the muscles rapidly occurs so that the condition of such person becomes progressively worse.

A principal object of the present invention is to provide an improved apparatus whereby vibrational and stimulating movement may be given to all parts of the body without the necessity of the individual having to exert any effort, so that the muscles and tissues will be vibrated and worked as though the person were indulging in active physical exercise, so that the massaging actions necessary to the maintenance of proper circulation and body tone are obtained.

Another object of the invention is to provide an apparatus by means of which stimulating massage may be given to the body in a smooth and steady manner and without subjecting the body to any sudden jerks or jarring movement, thereby making it possible for persons in a greatly weakened condition to be treated.

A further object of the invention is to provide an apparatus of the character stated employing a plurality of straps or belts which are connected with or are in contact with the body, with means whereby a proper degree of contact will be maintained between the belt and the body at all times to thereby prevent sudden jarring or slapping of the body by the belts as the same are manipulated by the apparatus.

Still another object of the invention is to provide a novel vibration apparatus in which a novel means is employed for connecting the vibration imparting straps with the power unit of the apparatus so that vibration will be transmitted through the straps to the body simultaneously with the movement of the straps on the body for massaging the same.

A still further object of the invention is to provide a novel body support or table for facilitating the administration of the stimulating massaging movements to the body by the straps con-

2

nected the body with the power unit of the apparatus, such table or body support being so constructed as to cooperate with the power unit and straps to maintain the straps at all times in the desired contact with the body.

Another object of the invention is to provide in a vibrating apparatus of the character stated, a novel support or table for both the power unit of the apparatus and the patient, whereby the patient will be resiliently supported and such resilient supporting means will add to the vibrating and stimulating effect of the apparatus as a whole.

Still another object of the invention is to provide in a vibration apparatus of the character stated, a table or bed having associated therewith, at a side thereof, a resiliently supported bar across which the movement imparting straps connecting the power apparatus with the patient, are passed and by which they will be maintained constantly in the proper contact or connection with the body.

Other objects and advantages of the invention will become apparent as the description of the same proceeds and the invention will be best understood from a consideration of the following detailed description taken in connection with the accompanying drawings forming a part of the specification, with the understanding, however, that the invention is not confined to a strict conformity with the showing of the drawings but may be changed or modified so long as such changes or modifications mark no material departure from the salient features of the invention as expressed in the appended claims.

In the drawings:

Figure 1 is a view in top plan of a massage and vibration apparatus constructed in accordance with the present invention.

Figure 2 is a view in side elevation of the table showing a figure thereon and showing portions of the massaging belts or straps and one manner of applying the same to the patient.

Figure 3 is a view in top plan of the patient supporting table minus the board and slatted unit which are provided for application thereto.

Figure 4 is a longitudinal section of the table taken substantially on the line 4—4 of Figure 3.

Figure 5 is a sectional view taken on the line 5—5 of Figure 3.

Figure 6 is a sectional view through the arm or standard supporting one end of the strap supporting bar.

Figure 7 is a detail section taken on the line 7—7 of Figure 1.

Figure 8 is a detail perspective of a portion of one end of the table from which the body supporting unit is removed.

Figure 9 is a view in side elevation of the motor apparatus and base upon which the same is

mounted, showing adjustable supporting legs therefor.

Figure 10 is a fragmentary section taken on the line 10—10 of Figure 9.

Figure 11 is a view in perspective of one adjustable end unit for the motor and base.

Figure 12 is a view in plan, on a small scale, of a body support designed to be mounted in the frame of the table.

Referring now more particularly to the drawings, it will be seen that, in addition to the vibration or movement imparting straps, the apparatus of the present invention essentially comprises two parts or units which are designated A and B, the unit A including a power source and the plurality of elements, such as belts, straps or the like, through which the motion and the vibration impulses, are transmitted to a patient supported upon the unit B.

The unit A which may be referred to as the source of vibration and massaging motion, comprises a suitable base 10 upon which is mounted an electric motor 11 having the usual power or armature shaft 12.

Supported upon the base 10 in spaced relation and at each of the two ends of the motor 11, are the inner and outer bearing standards 13 and 14 respectively. Each two bearing standards 13 and 14 supports a zigzag shaft 15 and the inner end of each zigzag shaft 15 is operatively coupled with the adjacent end of the motor shaft 12, by a cone pulley unit 16.

Each zigzag shaft 15 is made up of the joined angle or obliquely directed arm portions 17 and surrounding the shaft at the ends of each arm portion, are the collars 18.

The crank-shaft 15 has connected thereto the massaging and vibration imparting straps 19 and 20. The straps 19 are directly connected with the arms while the straps 20 are indirectly connected therewith through the medium of an arcuate yoke unit which is generally designated 21.

The yoke 21 comprises a central relatively large ring 22 having the diametrical cross-bar 23 which at their ends extend beyond the sides of the ring 45 and are connected with quarter rings 24 and relatively small terminal rings 25.

Connected with a quarter ring 24 at each side of the large ring 22, is a series of rings 26, certain of which are coupled together by the straps 27. At one end of the series is a small coupling ring 28 which directly connects with the quarter ring 24, and at the other end of the series is the arm connecting link 29 through which an arm 17 of the shaft passes.

In order to prevent undue wear upon the links 29, the arms, which they encircle, are each housed in a bearing sleeve 30, which the link 29 directly engages.

The straps 20 and also the straps 19 may 60 be made of any suitable material but are preferably formed of woven material such as canvas or the like. At one end, each strap has a buckle 31 attached thereto whereby when the end is turned back and engaged through the buckle, there is formed a loop 32 in which may be engaged one of the rings 26, or such a loop may have connected therewith an end of a spring 33 which has its other end connected with a ring, as shown in Figure 1.

The straps 19 which are connected with the shaft arms directly, are of the same construction as the straps 20, having a buckle 34 secured thereto, adjacent to one end, to facilitate the formation of a loop 35 with which an end of the 75

spring 36 may be coupled. The other end of the spring is suitably formed to provide a ring 37 which engages around a sleeve 30.

As shown in Figure 1 the yoke 21 extends across or straddles the motor 11 so that when the motor unit is disposed to one side of the patient supporting unit B, the ring 22 of the yoke will be located substantially on the transverse center of the unit B.

In association with the straps 19 and 20 there is provided the relatively wide strap or belt 37 which may be of plain woven fabric or it may have incorporated in its structure, an electric resistant heating unit 38 to which may be connected an electric current conductor 39 for transferring current from a suitable supply source to the heater unit.

One end of the belt 37 is passed around a bar 23 of the yoke ring 22 and secured by fastening the turned end to the main body portion of the belt, in any suitable manner, such, for example, as by the use of a safety pin, designated 40.

At its opposite end, the belt 37 is provided with the short straps 41, each carrying a buckle 42 adjacent to its inner end, which, after the belt has been passed around the body of a patient, may be looped around one of the bars 23.

The unit B comprises a rectangular frame 43 having at each corner a supporting leg 44, of substantially S shape. The bottom free end of each leg is directed parallel with the floor and toward the opposite end of the structure as shown. These legs provide a spring-like or resilient support for the frame.

Extending upwardly from each leg 44 toward and secured to the overlying side rail 45 of the frame 43, is a brace arm 46.

In each corner of the frame 43 is a plate 47 having an aperture 48 to facilitate the attachment, as hereinafter described, of connecting elements carried by an auxiliary frame 49. The attaching devices by which the auxiliary frame 49 is supported within the main frame 43, comprise hooks 50 attached to the four corners of the auxiliary frame for engagement in the apertures of the plates 47.

The auxiliary frame 49 is of open construction and may include a web of bands or spring wires 51 upon which the person receiving treatment lies.

If desired, the hooks 50 at one or both ends of the auxiliary frame may form a part of a turn-buckle 52, by means of which the frame may be pulled tight in the table frame.

In conditions where a solid bed or table is desired, there may be substituted for the auxiliary frame 49, the solid top body 53, Figures 1 and 2, which is designed to fit within the frame 43 and which is connected to the plates 47 by the hook members 54 which are attached to the corners of this body.

Extending transversely of the underside of the table and connecting together the legs at the two ends of the structure, are the bars 55, with which are connected the ends of a platform 56 which extends lengthwise of the underside of the table top. Upon this platform 56 the unit A may be mounted, if desired, so that the vibration or motion transmitting straps 19, 20 and 37 may be extended upwardly either across the sides of the rails 43, for connection with the body of the person receiving treatment, or through the slatted auxiliary frame, as may be found most convenient or satisfactory.

The straps 19, 20 and 37 are of sufficient length

to be passed around the body of the person lying upon the table top and have the free ends brought back and secured to the body of the strap as shown in Figure 2.

For the purpose of maintaining the straps relatively firmly in contact with the body of the person receiving the treatment so that no jerks or sudden harsh movements will be transmitted to such body, there is provided upon one or both sides of the frame 43 the longitudinally extending, resiliently supported auxiliary rail 57. This rail 57 is mounted at its ends upon spring supports 58, which are coupled with the frame rail 45 so that the bar may be raised to an elevation above the rail 45, for use.

In using the apparatus the person to receive treatment lies upon the top of the table and the several straps 19, 20 and 37 are disposed across or connected with the body at the various parts which are to receive special attention as illustrated in Figure 2.

The straps may be connected with the body in any of several different ways. For example, the motor apparatus or unit A when disposed at one side of the table unit B, will be in position to have the straps extend directly under the patient and the free ends will be looped back and secured to the bodies of the straps by suitable securing elements such, for example, as the safety pins 59. When the two units are arranged in this relation, springs 60 are preferably connected between the quarter circle elements 24 nearest to the unit B, and the adjacent side edge of the platform 56, which is provided with suitable apertured ears 61 as shown, for this purpose.

Additional resilient massaging action may be provided by arranging the patient support or table unit with the auxiliary rail 57 on the side nearest to the motor unit and passing the several straps over the top of the rail 57, when the supports have been swung up to vertical position, so that the straps will bear down on the rail and the resilient supports will yield as the straps are pulled taut and will raise the rail and the straps, as the pull on the straps is relaxed.

As will be readily apparent, after the straps are applied to the patient and are pulled tight between the patient's body and the arm portions to which they are attached, when the zig-zag shaft is rotated a portion of each arm will be moving away from the patient as the opposite end portion of the arm is moving toward the patient and consequently when the links 29 and 37 are adjacent to the ends of the arms which are swinging away from the patient a slight pull or tug will be applied to the strap and this will be almost immediately relaxed by the slipping of the links lengthwise of the crank toward that end which is swinging toward the patient. This continued pulling and relaxing upon the straps will be repeated with great rapidity as the shaft and arm portions rotate and thus a massaging and vibration will be imparted to the patient's body. This action when accompanied by the application of heat as through the use of the heated strap or belt 37 will result in great benefit to the person receiving treatment.

Where the motor apparatus is mounted beneath the table, the slatted support 49 may be used and the straps may be extended upwardly between the slats of such support to pass around the patient's body or they may be passed upwardly on the two sides of the table and, by the use of a spring supported rail 57 upon each side of the table, may be passed over such rail. Thus

when the straps are further tightened or have pulls applied thereto by the crank-arms the spring supports for the rails 57 will yield and such rails will rise and fall with the tensioning and relaxing of the straps.

The motor apparatus may be placed at different elevations for the most convenient application of the treatment and for this purpose there are provided the two supporting units shown in Figure 9, each of which is generally designated 62 and is disposed transversely of the underside of the base 10 at an end thereof. Each of these supporting units comprises a top or head bar 63 of sufficient length to extend across the width of the base 10, with an upturned ear 64 at each end, designed to extend across the adjacent longitudinal edge of the base. Each of these ears is provided with a threaded opening for the reception of the wing screw 65 the free end of which is directed inwardly toward the opposite ear.

Adjacent each end of the bar 63 is a down-turned ear 66 to which is pivotally attached the upper end of a leg 67 which at its opposite or lower end is formed to provide the foot 68.

Also pivotally attached to each ear 66 is an end of a brace rod 69 which extends downwardly therefrom toward the opposite leg 67 where it is connected with a slide member 70, carried on such opposite leg member and provided with a binding screw 71 which engages against the adjacent leg 67 so as to hold the free lower end of the brace rod 69 in slidably adjusted position on the leg. With this construction it will be readily apparent that the lower ends of the legs may be spread apart or drawn together to lower or raise the elevation of the bar 63 as desired.

The opposite longitudinal edges of the base-board 10 upon which the motor is mounted, are preferably provided with the longitudinally extending grooves or channels 72 in which the inner ends of the wing screws 65 engage. In this manner the ends of the bar 63 may be firmly secured to the base and at the same time, when the unit is lifted, there is no danger of the screws slipping off or coming free from connection with the base.

From the foregoing it will be readily seen that after the straps have been placed in operative position as stated, the vibratory movements imparted to the straps, or the alternate tightening and relaxing of the straps, by the machine will impart the desired massaging and vibrating effect to the body of the person taking the treatment. By reason of the resiliently supported rail 57 across which the straps may be passed, the straps will be maintained under a slight degree of tension even when the pull imparted thereto by the machine is relaxed. Thus it will be seen that there will be avoided the application of sudden pulls or jerks upon the body of the person to which the straps are attached so that the massaging action is at all times smooth and rhythmical.

By reason of the resilient legs for the table, it will also be seen that the patient's body will be so supported that outside jars or vibrations will not be transmitted thereto so that the total effect to be obtained is one of soothing gentle vibration and massaging.

I claim:

1. A therapeutic apparatus of the character described, comprising the combination of a table, a long member at a side thereof and resiliently

supported at its ends for movement toward and away from the table, a power unit including rotatable elements disposed oblique to the axis of rotation, and motion imparting flexible strap-like bodies connected to the rotatable elements and adapted to pass over and be held taut by said member when connected between the driven elements and a body lying upon the table.

2. A therapeutic apparatus of the character described, comprising the combination of a table frame, a top suspended within said frame and adapted to support a human body, an auxiliary side rail for the frame and resiliently connected thereto for movement toward and away from the frame, said auxiliary rail being normally urged outwardly from the frame, a power unit supported adjacent to said top and including motion transmitting driven elements, and motion imparting flexible, strap-like bodies connected with said driven elements and adapted to extend therefrom across and be drawn taut by the urge of said auxiliary rail to move outwardly, when connected between the driven elements and a body lying upon the table.

3. A therapeutic apparatus of the character described, comprising the combination of a table designed to support a human body, an auxiliary side rail disposed adjacent to and in parallel relation with a side of the table, resilient means connecting the ends of the auxiliary rail with the adjacent side of the table and constantly urging such auxiliary rail outwardly from the table, a power unit supported adjacent to the table and including motion developing driven elements, and flexible strap-like bodies connected to the driven elements and adapted to pass across and be held taut by said member, when connected between the driven elements and a body lying upon the table.

4. A vibration device of the character stated, comprising a motor having a rotatable shaft, a zig-zag shaft having a number of portions operatively coupled with each end of the motor shaft and supported to be rotated thereby, a yoke having two ends each connected with a section of said zig-zag shaft, a plurality of motion and vibration imparting straps, and a connecting means between an end of each strap and said yoke, the straps being connected with the yoke throughout the extent of the yoke between its two ends.

5. A therapeutic apparatus of the character stated, comprising a zig-zag shaft having a plu-

rality of relatively long arm portions, the arm portions extending oblique to the rotary axis of the shaft, a strap member designed to encircle the body or a member of a patient under treatment, and a link carried at an end of the strap, and having loose connection with an obliquely angled arm portion, the strap when in use being substantially taut between the arm portion and the body of the patient whereby the arm portion will effect the alternate tightening and relaxing of the strap.

6. A therapeutic apparatus of the character stated, comprising a rotatably supported shaft, said shaft having relatively long joining arm portions disposed obliquely to the length of the shaft, means for rotating the shaft, a relatively long yoke member having a link at each end, each of said links having one of two widely separated arm portions passing therethrough, a plurality of straps, and means connecting each of said means connecting the straps with the member at one end to said member, the straps being substantially equidistantly spaced throughout the length of the member.

7. A therapeutic apparatus of the character stated in claim 6, with a bearing sleeve encircling each of the arm portions which passes through a link, the link having loose connection on the adjacent sleeve for sliding movement lengthwise thereof during the rotation of the shaft.

8. A therapeutic apparatus of the character set forth in claim 6, in which one of said straps is of substantial width, and an electrical resistance heater built into the said one of the straps.
